UNITED STATES PATENT OFFICE.

MILLARD FILLMORE CRAWFORD, OF NATALBANY, LOUISIANA.

LOG-UNLOADING MACHINE.

Application filed September 7, 1926. Serial No. 134,041.

The present invention relates to log unloading machines, and has for an object to provide a novel means for controlling the position of a ram cylinder, such as is disclosed 5 in my co-pending application, Serial No. 110,941, filed May 22, 1926.

Another object of the invention is to provide controlling means for the ram cylinder, which is located adjacent to the throttle lever, 10 so that one operator may not only control the thrust of the ram cylinder but may also from the same position control the angular movements, or the swinging of the ram cylinder either before or during its operation.

15 A further object of the invention is to provide a tilting or swinging means for a ram cylinder which may be actuated by a fluid, such as air, steam or the like under suitable pressure, so that both the ram cylinder and the tilting device may be controlled from a 20 single source of fluid pressure and be under the complete control of one operator.

25 A further object of the invention is to provide a tilting cylinder for connection with the ram cylinder for holding the latter in any position of adjustment desired and in which the ram cylinder is to be used so that the latter may be operated from any desired 30 position and the operation of the ram cylinder and the tilting cylinder do not interfere with one another.

The invention still further aims to provide 35 an improved tilting device which is capable of swinging the ram cylinder into an upright position, and providing means for locking the ram cylinder in such position, so that it may be carried out of the way when not in use, and to further provide a fluid actuated tilting cylinder, which is capable of flexibility in use, and to further provide the cylinder with means for reducing the pressure when the latter reaches a predetermined degree to prevent injury to the mechanism when the ram cylinder is swung out of adjusted position by abnormal weights imposed 45 thereon, such as by logs.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of a log unloading machine constructed according to the present invention, the top or cover being removed.

Figure 2 is a side elevation of the same, and

Figure 3 is a front elevation of the device in position for unloading logs from a car.

In the present instance the invention is shown as applied to a log unloading machine of the portable steam operated type, such as shown in my co-pending application Serial No. 110,941, above referred to. It is understood, however, that the present invention may be applied to any type of log unloading machine utilizing a ram, and which may be operated by other pressure than steam and which may be self-contained and otherwise than portable if desired.

Referring to the drawings, 10 designates a platform supported on the wheels 11, which in the present instance are mounted on a track 12, so that the device may be of a portable nature if desired. The platform 10 may have a steam boiler 13 thereon with a water tank 14 and a fuel tank 15 suitably disposed on the platform, and the platform may also be provided with an engine 16 adapted to be connected to the boiler 13 by a steam supply pipe 17.

These elements so far described are merely for the purpose of illustration and, of course, may be substituted by any other suitable frame work or support, and any other suitable means of supplying fluid under pressure.

The platform 10 is provided with a pair of uprights 18 between the upper ends of which is mounted a ram cylinder 19, the latter being supported on trunnions 20, which have bearing in the upper ends of the standards 18, and the standards 18 are preferably reinforced by braces 21, which extend from the upper ends of the uprights 18 downwardly to the base 22 of the frame so formed.

The ram cylinder 19 is adapted to swing on the axis of its trunnions 20 and is provided with a head 23 of suitable construc-

tion to engage logs or the like mounted on a piston rod 24, which carries the piston 25 movable lengthwise in the cylinder 19. A throttle valve 26 is mounted upon the cylinder 19 adjacent to the trunnions 20 and is connected by a feed pipe 27 with the boiler 13 through the trunnions 20 at one side, and with the exhaust pipe 28 through the trunnion 20 at the opposite side. As the throttle 5 valve 26 is arranged adjacent to the trunnion 20 the movement of the throttle valve is very slight upon the pivotal movement or swinging of the ram cylinder 19. A throttle lever 29 projects from one side of the throttle and 10 terminates adjacent to the axis of the trunnion 20 to facilitate manipulation of the ram cylinder 19.

The throttle valve 26 is connected by pipes 30 to the opposite ends of the ram cylinder 19 for controlling the intake and exhaust of steam into and from the opposite ends of the ram cylinder. The ram cylinder 19 is adapted to be swung upwardly from the horizontal position, shown in Figure 3, into 15 a substantially vertical position, and the ram cylinder carries a pin 31 near its rear end adapted to interlock with a latch 32 mounted on the base 22 and the lower ends of the standards 18, so as to lock and hold the ram cylinder in vertical position out of the way. Further, the standards 18 are provided intermediate their ends with a cross brace 33 carrying a buffer spring 34 adapted to engage the rear end of the ram cylinder 19 when 20 the latter is swung upwardly at its forward end.

The present invention provides a means for swinging and holding the ram cylinder in the desired position upon its axis 20. For this purpose, the ram cylinder frames 40 are provided with upstanding brackets 35, which may be of A form or otherwise, and which are disposed at opposite sides of the ram cylinder 19 at its rear end. The brackets 35 carry in their upper ends bearings 36 supporting trunnions 37 carried upon the lower head of a cylinder 38 adapted to swing upon the trunnions into different angular positions upon the brackets 35. The cylinder 38 is the swinging cylinder for operating the ram cylinder 19 and is provided with 45 a piston 39 having a piston rod 40, which projects downward through the lower head of the cylinder 38 and is pivotally connected to a yoke 41 having its arms pivoted at 42 to the forward portions of the brackets 35 at opposite sides of the ram cylinder 19.

The free end of the yoke 41 has a roller 43, which bears upon a spring wear plate 44 secured to the upper side of the ram cylinder 19 and extending from a point near the rear end of the ram cylinder forwardly thereof, the spring wear plate 44 being bent upwardly at an angle at its forward end to maintain 50 the same in engagement with the roller 43

as the ram cylinder 19 is swung upwardly into vertical position by the cylinder 38.

The trunnions 37 of the swinging or tilting cylinder 38 are also of hollow construction to conduct the intake and exhaust steam 55 for operating the cylinder 38. A steam supply pipe 45 leads from the steam boiler 13 to one trunnion 37 and from the latter the steam supply pipe 46 carried by the cylinder 38 leads to a controlling valve 47 mounted 60 intermediately upon the cylinder 38, and which is connected by pipes 48 to the opposite ends of the cylinder 38. It will also be noted that the controlling valve 47 has an exhaust pipe 49 which leads to the opposite trunnion 37 and steam is carried there-through to the outlet or exhaust pipe 50.

The controlling valve 47 is provided with an operating lever 51 at one side which normally extends outwardly and upwardly at a slight angle, and which is connected to a differential lever 52. The lever 52 is of suitable length and is pivotally connected at 53 to an upstanding rod 54, which is pivotally mounted upon the yoke 41 intermediate the pivotal and free ends thereof. The swinging movement of the yoke 41 raises and lowers the rod 54 and thus swings the differential lever 52.

The differential lever 52 is pivotally connected intermediate its ends, and preferably toward the valve controlling lever 51, with an anchoring link 55, which is pivotally carried upon an arm 56 mounted on a shaft 57 supporting upon a bracket 58 which is carried by the cylinder 38.

The shaft 57 projects laterally from the arm 56 and carries a second longer arm 59, which extends downwardly and across the axis of the trunnion 37 and is pivotally connected a short distance below the trunnion 37 with a push rod 60. The rod 60 is relatively long and extends downwardly through the adjacent bracket 35 and into the ram cylinder frame, and is pivotally connected to an arm 61 of a rock shaft 62 mounted in a bracket carried by the platform 10 and adjacent to one of the standards 18. The rock shaft 62 extends upwardly from the standard 18 into a suitable position for supporting an upright tilting lever 63 adjacent the operator.

In operation, when it is desired to tilt the ram cylinder 19, it is only necessary for the operator to swing the tilting lever 63 through a desired angle and maintain the lever 63 in such adjusted position. This operation causes the push rod 60 to move upwardly and swing the arms 59 and 56 upwardly to move the anchoring link 55 in an upward direction and swing the differential lever 52 upwardly about its pivot 53. This action causes the differential lever 52 to not only move inwardly toward the controlling valve 47, but to also swing the throttle lever

51 upwardly a predetermined extent. Such action admits steam to the upper end of the cylinder 38 to force the piston 39 downwardly, swing the yoke 41 and urge the roller 43 against the spring wear plate 44, depressing the inner or rear end of the ram cylinder 19.

As the ram cylinder 19 is swung downwardly at its rear end, the yoke 41 swings 10 the tilting cylinder 38 into an angle about its trunnions 37, so that the piston rod 40 may exert a more nearly direct thrust upon the top of the cylinder 19. This action of the yoke 41 causes the same to swing downwardly and draw the rod 54 downwardly therewith, swinging the differential lever 52 about its pivotal connection with the anchoring link 55 and operating the throttle lever 51 to close off the supply of steam to 15 the cylinder 38. This operation also holds the ram cylinder 19 in adjusted position until the lever 63 is swung into a new position or back into its original normal position, as shown in Figure 3.

25 The mechanism, therefore, allows the operator to move the lever 63 into a desired position and leave it in such position whereupon the valve mechanism automatically effects the entrance of the fluid under pressure 30 into the desired end of the cylinder 38 and to the desired extent to move the ram cylinder into the angle desired, and then cutting off the supply of fluid pressure to the cylinder 38 for yieldingly holding or locking the 35 swinging mechanism in position. The end of the cylinder 38 may be provided with a pressure relief valve 64 adapted to relieve pressure in the cylinder when an abnormal load or pressure is placed upon the head 23, 40 such as by the falling of logs or the like thereon, and which would otherwise damage the apparatus.

This arrangement and location of the 45 pressure relief valve 64 thus serves to protect the mechanism, and may be adjusted so as not to interfere with the normal working of the cylinder.

Figure 3 of the drawings shows one working position of the ram cylinder 19 wherein 50 the head 23 is disposed opposite to a load of logs 65 mounted on a truck or car 66, which is disposed adjacent to the log unloading machine, anchoring chains 67 being utilized if desired for holding the platform 55 10 and the car 66 from spreading apart under pressure of the ram cylinder.

It will be noted particularly from Figure 60 3 that the ram cylinder 19 has its trunnion 20 between the ends of the ram cylinder, but nearer the inner end thereof, so that the weight of the outer end of the ram cylinder with the head 23 is sufficient to at all times normally urge the rear end of the ram cylinder upwardly against the work member

41. Thus the piston 39 need act only in a 65 downward direction.

It is obvious that various changes and modifications may be made in the details of construction and design of the above specifically described embodiment of this invention without departing from the spirit thereof, such changes and modifications being restricted only by the scope of the following claims.

What is claimed is:—

1. In a log unloading machine, a ram cylinder, means for pivotally supporting the ram cylinder intermediate its ends but at a point toward its rear end whereby to normally urge the rear end of the ram cylinder to extend upwardly, a tilting cylinder mounted above the rear end of the ram cylinder and having a piston rod projecting downwardly toward the ram cylinder, a yoke member pivotally mounted between the cylinders and having one end pivotally connected to said piston rod for urging the end of the yoke against the upper side of the ram cylinder, a spring wear plate carried upon the upper side of the ram cylinder beneath the yoke for receiving impact thereof and absorbing shock incident to the pounding of the piston rod, and means for controlling admission of fluid under pressure to the tilting cylinder.

2. In a log unloading machine, a ram cylinder, means for pivotally supporting the ram cylinder near its rear end, a tilting cylinder disposed above the rear end of the ram cylinder, means for pivotally supporting said tilting cylinder, means for conveying fluid under pressure through the supporting means to the tilting cylinder, a controlling valve mounted on the tilting cylinder for admitting fluid under pressure to 100 and from the opposite ends thereof, a differential lever connected to the controlling valve, a supporting rod pivotally connected to the differential lever in spaced relation to the valve, hand controlled means connected to the differential lever for swinging the same upon its pivotal connection with said rod, and automatic means connected to the rod and between the cylinders for swinging the differential lever into a normal position 105 incident to the movement of the tilting cylinder into a position corresponding to that in which said hand controlling means is adjusted.

3. In a log unloading machine, a ram cylinder, means for pivotally supporting the ram cylinder at a point near its inner end, a tilting cylinder pivotally mounted above the rear end of the ram cylinder, a swinging member having a fixed pivot adjacent the ram cylinder and engaging at its free end the rear end of the ram cylinder, a piston rod carried in said tilting cylinder

and connected to said pivoted member for urging the same downwardly against the ram cylinder, fluid controlling means carried by the tilting cylinder, manual means for setting the fluid control means for operating the tilting cylinder to tilt the ram cylinder, and automatic means connected to

said pivoted member and to said fluid controlling means and said manual means to bring the fluid controlling means into normal inoperative position when said tilting cylinder reaches the desired position of adjustment.

MILLARD FILLMORE CRAWFORD.
